UNITED STATES PATENT OFFICE

157,668

PENDANT OR THE LIKE

Henry Gorman, Providence, R. I.

Application December 6, 1949, Serial No. 6,441

Term of patent 14 years

(Cl. D45—17)

To all whom it may concern:

Be it known that I, Henry Gorman, a citizen of the United States, residing at Providence, county of Providence, and State of Rhode Island, have invented a new, original, and ornamental Design for Pendant or the like, of which the following is a specification, reference being had to the accompanying drawing, forming a part thereof.

Figure 1 is a side elevation of a pendant or the like, embodying my new design;

I claim:

The ornamental design for a pendant or the like, as shown.

HENRY GORMAN.
